UNITED STATES PATENT OFFICE.

CARL OSKAR SANDBERG, OF OREBRO, SWEDEN.

BORING BIT.

Application filed March 17, 1926, Serial No. 95,175, and in Sweden February 11, 1925.

The present invention relates to a boring bit which is intended to replace the usual so-called spoon-bit or duck-nose bit, and simultaneously to render the bit suitable for use 5 also for other materials than wood. The usual spoon-bit is provided with a flute-shaped cavity, one of the edges of which forms the cutting edge of the bit and the other of which forms the so-called back edge, 10 said edges being located approximately diametrically opposite each other relatively to the axis of the bit and being directed towards the same side, the bit having a convex spherically rounded end the edge of which forms a 15 continuation of the cutting edge which latter thus runs over, through an approximate semi-circle, into the back edge at the end of the bit. It is thus this semi-circular portion which is put against the wood when the bit is 20 used. It is a generally experienced fact, however, that a spoon-bit of this old type does not remain in the center against which the bit was placed, but the bit will move around such center with the result that one is 25 never sure to get the hole drilled at the exact desired point. Such spoon-bits will also as a rule splinter the wood on the back of the piece when the bit cuts through the same.

The purpose of the present invention is to 30 produce a bit which is not encumbered with the disadvantages above mentioned, and by means of which it will be easy to drill a hole at the exact desired point and which will also produce smooth and clean holes without 35 splintering or splitting the wood on the upper side or the lower. For this purpose the bit is broadly characterized by the fact that the edges of the flute-shaped cavity, which are parallel over part of their 40 length, towards the end of the bit run out into a sharp point located on the axis of the bit, and are all the way out to said point in or approximately in one and the same plane through the axis of the drill.

An embodiment of a bit according to the 45 invention is illustrated in the accompanying drawing. Fig. 1 shows an elevation of the bit viewed towards the cavity, Fig. 2 is a cross section on the line II-II in Fig. 1, and Fig. 50 3 is an elevation at right angles to that shown in Fig. 1.

As will be evident from the drawing, the shape of the present bit corresponds to the shape of an ordinary spoon-bit in so far as it 55 has a cutting edge 1 which is parallel to the axis of the bit at least in respect of part of its length. Approximately diametrically opposite said cutting edge 1 is the so-called back edge 2 of the bit which is also parallel to the axis of the bit at least in respect of part of its length, and between the cutting edge and the back edge is the flute-shaped cavity 3. The cutting edge 1 is at a greater radial distance than the back edge 2 from the axis of the bit and is also suitably slightly in front of the diametral plane through the back edge, as shown in Figs. 2 and 3. The outer surface 4 of the bit between the cutting edge 1 and the back edge 2 is substantially cylindrical.

According to the invention the end of the bit is tapered substantially conically to a sharp point 5 located on the axis of the bit, in which point the cutting edge 1 as well as the back edge 2 and the outer surface 4 of the bit and the surface of the cavity 3 meet, as shown in Figs. 1 and 3. Owing to this conically pointed shape the bit will always remain in the center in which it was put, and the bit will give clean and smooth holes and will not splinter or split the wood either on the upper side of the same where the bit penetrates into the wood, or on the lower side of the piece when the bit cuts through the wood. It has also been found that with the present 85 bit it is possible to bore holes more rapidly than with ordinary spoon-bits.

The upper end of the bit may be given a conical or other suitable shape for enabling the bit to be mounted in a brace or boring machine, 90 or the bit may be provided with a handle in which manner the bit becomes a very practical hand tool which may find a many-sided use in different trades, such as by carpenters, electricians, machinists, harness-makers, up- 95 holsterers, farmers, or in the homes.

I claim:

1. A boring bit having a flute shaped cavity, the front edge of said cavity constituting a cutting edge and being at a greater radial 100 distance from the axis of the bit than the back edge, said edges converging in a point in the axis of the bit.

2. A boring bit, having a flute-shaped cavity, the edges of said cavity being located substantially opposite each other relatively to the axis of the bit and being directed towards the same side, one of said edges forming the cutting edge of the bit and the other forming the back edge of the bit, said cutting edge being at a greater radial distance from the axis of the bit than the back edge, said

edges being parallel over a portion of their length and running out towards the end of the bit into a sharp point located on the axis of the bit, said edges being all the way out to 5 said point substantially in a plane through the axis of the bit.

3. A boring bit as claimed in claim 2, in which the cutting edge is located slightly in front of the diametral plane through the back 10 edge.

4. A boring bit having a flute shaped cavity, the front edge of said cavity constituting a cutting edge and being at a greater radial distance from the axis of the bit than the back edge and also being located slightly in 15 front of the diametrical plane through said back edge, said edges converging in a point in the axis of the bit.

CARL OSKAR SANDBERG.
